G. G. FLOYD

FOUNTAIN LATHER BRUSH

Filed March 2, 1921

Fig. 3.

Inventor:
George G. Floyd
By Walter M. Fuller
Atty.

UNITED STATES PATENT OFFICE.

GEORGE G. FLOYD, OF RIVERSIDE, ILLINOIS.

FOUNTAIN LATHER BRUSH.

Application filed March 2, 1921. Serial No. 448,984.

To all whom it may concern:

Be it known that I, GEORGE G. FLOYD, a citizen of the United States, residing at Riverside, in the county of Cook and State 5 of Illinois, have invented certain new and useful Improvements in Fountain Lather Brushes, of which the following is a specification.

My invention relates to fountain brushes 10 in general, but concerns more particularly, although not restrictedly, brushes of this general type designed for the application of lather preliminary to a shaving operation.

To this end, the supply of soap or shaving 15 cream is contained in the handle of the brush and is delivered in small quantities as occasion requires to the bristles of the brush, ready for the formation of the lather.

One object of the invention is to be able 20 to use a collapsible supply tube whereby the soap or cream is always maintained in a cleanly and sanitary manner until actually used.

A further purpose of the invention is the 25 employment of a suitable valve to control the discharge or delivery of the soap or cream to the brush and to prevent an unintentional feed thereof to the brush.

Another salient characteristic of the 30 appliance embodying the invention is the employment of means to assure the collapse of the compressible supply tube without increasing any of its transverse dimensions, or, differently stated, confining the width of 35 the collapsed portion of the tube so as not to exceed its original diameter.

An additional outstanding feature of the 40 invention resides in an improved cover for the brush which may be applied and removed with facility and dispatch and which permits the brush to stand with its bristles disposed downward to aid their draining and drying.

In order that those skilled in this art 45 may have a full and complete understanding of the manner in which the foregoing and other desirable advantages of the invention are obtained in a structure embodying the invention in question, I have illustrated in the accompanying drawing a preferred and desirable embodiment of such invention, like reference characters throughout the several views applying to the same parts.

50 In this drawing:

Figure 1 is an elevation of the complete

fountain brush with the bristle cover in position;

Figure 2 shows the same with the cover removed illustrating the brush portion 60 proper;

Figure 3 is a fragmentary central longitudinal section through the appliance with the brush cover removed;

Figure 4 is a horizontal section on line 65 4—4 of Figure 3; and

Figure 5 is a plan view of the rider or bridle employed in connection with the collapsible supply tube.

Referring to the drawing, it will be perceived that the structure comprises a sheet-metal cylindrical shell 11 open at one end and provided at its opposite end with a circular rib 12, an adjacent external annular groove 13, and an inwardly-converging, 70 centrally-apertured end-wall 17 fastened securely to a round supporting member 18 internally screw-threaded to detachably or removably receive the threaded neck 19 of a substantially-cylindrical, collapsible supply- 75 tube 21 containing a charge of soap or shaving cream.

Such supply-tube is intended to be concealed or housed in a cylindrical sheet-metal cover 15, having an inturned edge portion 80 at 14, and longitudinally slit at a plurality of points at 16 to give the open end of the cover a degree of elasticity, whereby it may be sprung over the bead or rib 12 and detachably held in position by the part 14 85 fitting in the groove 13 behind the rib.

The two parts 17 and 18 may be most conveniently secured together by fitting a reduced portion of the latter in the central hole of the former, and then upsetting such 90 part as is fully depicted in Figure 3.

Element 18 also has a threaded aperture 22 receiving the corresponding threaded terminal part of a tube or pipe 23 and holding the longitudinal passage through the 100 same in register with the mouth of the supply-tube.

The upper or outer end of such tube or pipe is closed, but it has two lateral apertures 24 through which the soap or cream 105 may be expressed into the central portion of the brush, the tube or pipe having an enlarged head 25 with a central groove 26 for the application of a screw-driver when the pipe is applied to or removed from the 110 member 18.

A brush head or base element 27 has a

round part adapted to fit and slide in the shell 11, an enlarged hollow rib 28, and an inturned portion 29 designed to firmly grip and hold the base portions of the bristles of 5 the brush.

Internally the member 27 accommodates a sheet-metal element having a cylindrical portion 32 fastened to the inner face of the part 27, an intermediate disc portion 31, and 10 a valve sleeve 33 fitting over and adapted to slide on the pipe or tube 23 to open and close the valve ports or openings 24.

The brush proper 34 is composed of suitable bristles whose inner ends are securely 15 held between the parts 27, 28 and 29 and the valve sleeve 33, whereby the latter and the brush are fastened together and are adapted to move in and out as a unit.

To normally maintain the brush in projected position and the valve ports closed, a 20 coil-spring 35 is interposed between the elements 17 and 31, surrounding the support 18.

In order to prevent the collapsible supply-tube 21 from expanding or enlarging in any 25 direction when it is squeezed to deliver a portion of its contents through the delivery pipe 23, it is equipped with a tapered confining rider or bridle 36 constructed of a band of flexible sheet-metal, one end of 30 which has a slot 37 therethrough for the reception of a tongue 38 on the other end of the band, the tongue or lip 38 being bent back after passing outwardly through the slot to hold the ends of the band together 35 adjustably and to give the rider a definite size conforming to that of the tube with which it is used and around which it is fitted as shown.

Internally, the confining rider has two, 40 opposite, longitudinally-tapered, hollow ribs 39, 39, made of suitably-shaped sheet-metal members having top and bottom tongues or lips 41 and 42 bent over the corresponding edges of the element 36 to hold 45 or maintain the ribs in position.

The open-ended cover 42 for the bristle portion of the brush comprises two, sheet-metal substantially semi-cylindrical shell elements 43 and 44 hinged together at 47 by 50 an eyelet passing through overlapped ears 45 and 46, the cover near one end having a hollow bead 48 adapted to fit over the annular rib 28 of the brush, with the portion 49 of the cover between such rib and the 55 shell 11.

At such end of the cover, the one element 44 has ears 51 on its opposite sides overlapping the companion element of the cover and provided with indentations 52 forming internal bosses adapted to fit in recesses of 60 the parts which they overlie.

The other or outer end of the cover is flat and open, the edges of the two parts do not touch in the contracted or closed condition 65 of the cover leaving longitudinal openings

53, and in addition the cover has ventilating slits 54, all as is clearly illustrated in Figure 1.

The operation of the improved and novel style of brush occurs practically as follows:

The rider or bridle 36 is clamped around the lower portion of a soap or cream supply-tube 21 and forced part way along the same towards its neck to provide substantial external grooves in the tube by the ribs 39.

Such infolding of the thin metal at these two opposite points assures that when the tube beyond or below the rider is squeezed or collapsed to expel its contents, the tube will not expand sidewise beyond the original 80 diameter of the tube.

This permits the employment of a cover over the tube not much larger in diameter than the tube itself.

The supply-tube having thus been fitted 85 with the groove-producing or metal-folding band or strap, the neck of the tube 19 is screwed into the threaded socket in the supporting member 18.

To feed some of the soap or cream to the bristles, the brush 34 and its head or base are pushed inwardly with one hand causing the valve sleeve 33 to open the valve ports or apertures 24, and at the same time with his other hand the operator squeezes or compresses that part of the tube below or beyond the rider, thereby expelling into the brush proper any desired quantity of the tube's contents.

As soon as this has been accomplished, the brush is released and the valve immediately closes automatically, thus effectually preventing any further discharge of the soap or cream, which sometimes tends to occur with collapsible tubes of this character.

Thereupon, the cover or handle part 15 may or may not be attached to the appliance over the tube and the brush structure as a whole employed in the usual way, although some persons prefer to omit the application of the handle cover and to use the supply tube itself as a handle.

From time to time as occasion requires, the bridle or rider 36 is forced along the tube to preliminarily form the side grooves 115 or deformations in the tube before the latter is collapsed or compressed to feed its contents.

The use of the brush having been completed and its bristles having been washed 120 or rinsed to remove the surplus lather as is customary, the hinged cover is applied over the brush by turning its hinged sections together over the bristles, thus more or less automatically compressing the brush which 125 has a natural tendency to expand.

The complementary parts of such cover are held in this closed relation by the co-operating catches or locks 52 and the presence of a portion of such cover between the 130

bead 28 and the end of the shell 11 prevents the inward movement of the brush and consequently prevents the opening of the soap or cream supply valve.

5 Accordingly there is no danger of a discharge of the contents of the tube so long as the bristle cover is in place.

10 If any of the bristles tend to project through the slits or cracks in the cover, they can be easily withdrawn therefrom by merely turning the cover somewhat on its own axis.

15 Inasmuch as the end of the cover is positioned slightly beyond the ends of the bristles, is open, and is flat, the whole structure may be caused to stand on such open end thus facilitating draining of the wet or damp bristles.

20 Those skilled in this art will readily understand that the invention is not limited and restricted to the precise structure shown and described since radical changes may be made in the same without departure from the substance and essence of the invention 25 and without the sacrifice of any of its substantial benefits and advantages, and it will be furthermore understood that the brush itself is not confined to the particular use specified since it is capable of satisfactory 30 employment in many relations.

The collapsed or flattened part of a supply tube of the type indicated is of a width ordinarily more than one and one-half times the original diameter of the tube, and one 35 purpose and function of the progressively

advanced rider or confiner is to prevent such sidewise expansion during the flattening of the tube. In the present embodiment of the invention the width of the collapsed part of the tube is confined or restricted to the original diameter of the tube, but, of course, reasonable variations are permissible. 40

I claim:—

1. In a fountain-brush, the combination of a shell, a brush including bristles and a 45 hollow brush-head slidable with relation to said shell, an internally-threaded member in said shell adapted to receive the threaded neck of a collapsible supply tube, a pipe with a valve-port connected to said member 50 and extending through the hollow of the brush for the passage of the contents of the tube to the bristles, a valve sleeve in said brush-head encasing and slidable on said pipe and adapted by its reciprocations to 55 open and close said valve-port, and a spring acting on said brush-head tending to shift the latter to valve-port closing position.

2. In a fountain-brush, the combination of a support, a brush slidably mounted on 60 said support, a supply member, means to conduct the contents of said supply member through a discharge opening to said brush, a 65 slidable valve controlling said discharge opening of said conducting means by the sliding movement of said brush, and a removable cover for said brush locking the latter against sliding valve-opening movement when in position over the brush.

GEORGE G. FLOYD.
